TOLL SERVICE TRUNKING SYSTEM

Original Filed June 16, 1923 3 Sheets-Sheet 3

UNITED STATES PATENT OFFICE.

JOHN WICKS, OF OAK PARK, ILLINOIS, ASSIGNOR, BY MESNE ASSIGNMENTS, TO AUTOMATIC ELECTRIC INC., OF CHICAGO, ILLINOIS, A CORPORATION OF DELAWARE.

TOLL-SERVICE TRUNKING SYSTEM.

Application filed June 16, 1923, Serial No. 645,714. Renewed June 18, 1927.

The present invention relates in general to telephone systems, but is particularly concerned with certain conditions which arise when a portion of the offices of a manual system are changed over to automatic. When this is done some special means must be provided to enable the operators at the toll office to complete incoming toll connections to subscribers of the automatic offices. In some instances this has been accomplished by providing such toll operators with the proper impulse sending apparatus, which method is satisfactory under certain conditions. Local conditions however are sometimes such that the added cost of installing this apparatus at each toll operator's position is excessive, or the toll operators are already taxed to their capacity and therefore would not be able to give efficient and speedy service were this burden added. The object of the invention therefore is to provide means whereby it is unnecessary to provide the toll operators with impulse sending equipment, but instead when a call is received for a subscriber located in an automatic office the operator repeats the desired number to a B operator in that office, the B operator having the proper impulse sending apparatus to complete the connection.

Another object lies in the provision of novel supervisory control circuits, which enable the toll operator to have full supervision of the call after the B operator has transmitted the impulses required to obtain the wanted subscriber.

Referring to the drawings, Fig. 1 shows an incoming toll line X, an outgoing trunk Y, and a cord circuit for linking the two together.

Fig. 2 shows a B operator's equipment for setting up an automatic switch train, and a selector switch D.

Fig. 3 shows a final or connector switch, a line switch C and a called line A.

The cord circuit O, Fig. 1 is of a type commonly used by toll operators in manual systems for answering incoming calls as well as for completing toll connections.

The group of relays in the outgoing trunk Y shown at the right of Fig. 1, together with the two interrupter devices I and I' are for controlling a supervisory signal as will be fully described subsequently.

The B operator's calling device C, D (Fig. 2) is of the type in common use at the 55 substations of modern automatic telephone systems.

The selector D (Fig. 2) in the automatic office is mechanically of the well known Strowger type and accordingly has its bank 60 contacts arranged in horizontal rows or levels. The circuit of the said selector is shown complete and will be fully described hereinafter.

The connector H, Fig. 3 is of the well 65 known Strowger, vertical and rotary type which may be seized by means of a selector such as the selector D in order to complete connections to called stations such as the one shown at A.

The apparatus having been described in general, a detailed description will now be given. For this purpose it is assumed that the toll operator at the toll office receives a call over the toll line X, Fig. 1. It is 75 further assumed that the desired station is station A (Fig. 3) in an automatic office. When a call comes in over the toll line X the ring down relay 3 is operated causing the lamp L to glow. The operator upon observing the lighted condition of lamp L responds by inserting the plug P of her cord O into the answering jack J. This results in the operation of cut-off relay 4 in series with the sleeve relay 5. Relay 4 in operating 80 opens the initial operating and locking circuits of ring down relay 3 and closes a circuit for the visual busy signal and all multiple visuals at other positions.

The operation of relay 5 closes a point in 85 the circuit of lamp 6 and in the locking circuit of ring up relay 7'. There is no battery normally flowing on trunk line X and therefore relay 7' will not be operated unless the operator in the distant office sends 90 ringing current over the trunk.

As soon as the operator plugs into the toll line she throws her listening key, and after ascertaining that the station desired is station A of an automatic office, operates the 100 button 7 connecting her order wire with the B operator of that office. The toll operator now repeats the desired number to the B operator at the automatic office. The B operator selects an idle outgoing trunk as indicated by the extinguished lamp, such as 105

the lamp 8, operates her calling device key K⁵ and assigns this idle trunk Y to the toll operator.

The B operator in operating her calling device key completed a circuit for the line relay 21 of selector D as follows: from grounded off normal springs 48, lower winding of line relay 21, armature 47 of relay 25 and its resting contact, springs 49 and 50 of the key K⁵, through the calling device C. D., springs 51 and 52 of the key K⁵, armature 46 and its resting contact, and the upper winding of line relay 21 to battery. Line relay 21 energizes and completes a circuit for slow release relay 22 which also energizes. Relay 22 in operating, at its upper armature grounds the release trunk 36 causing the lamp 8 at the B operator's position to glow, thereby indicating the busy condition of the trunk. Relay 22 also prepares the usual operating circuit for the series relay 23 and vertical magnet 28.

Referring now for a moment to Fig. 1, it will be seen that when the toll operator inserts the plug P' into the jack J' of the assigned trunk Y a bridge is completed across this trunk, extending from trunk conductor 18, springs controlled by armature 9 of relay 10, upper armature and working contact of relay 11, windings of relays 12, 13 and 14, and through contacts controlled by armature 16 of relay 10 to conductor 19. It will be evident that none of these relays are operative at this time because the trunk is open at springs 49 and 52 while the calling device key K⁵ is in operated position.

Now returning to the operation of the selector switch D, the B operator will now operate the calling device C. D. In accordance with the telephone number of the substation A. When the calling device dial is operated in accordance with the first digit of the number a series of interruptions is produced in the circuit of the line relay 21. Responsive to these interruptions in its circuit, relay 21 deenergizes momentarily and at each deenergization sends a current impulse through the slow acting series relay 23 and the vertical magnet 28 to battery. By the operation of the vertical magnet the shaft is raised step by step until the wipers 33 to 35, inclusive, stand opposite the horizontal level of bank contacts which are terminals of trunk lines leading to the desired group of connectors. The slow acting series relay 23 is energized in series with the vertical magnet, maintaining its armature continuously attracted during the vertical operation of the switch, and closes a circuit for the stepping relay 24. The stepping relay 24 is therefore energized, and when the off normal springs are shifted at the first upward movement of the switch shaft, establishes a locking circuit for itself by way of the off normal springs 38. At the end of the verti-

cal movement of the switch relay 23 is deenergized and completes a circuit for the rotary magnet 27, which extends from the grounded conductor 36 by way of armature 37 and its resting contact, armature 40 and its working contact and the winding of magnet 27 to battery. The rotary magnet is accordingly energized and advances the wipers 33 to 35, inclusive, into engagement with the first set of bank contacts in the level opposite which they were raised. Near the end of its stroke the rotary magnet breaks the circuit of stepping relay 24, which is accordingly deenergized to open the circuit of the rotary magnet. Both the stepping relay 24 and the rotary magnet 27 having deenergized, the operation now depends upon whether the test contact with which the test wiper 34 is in engagement is busy or is not busy. If this test contact is busy it will have a ground potential upon it and a circuit will be established which extends by way of the said test wiper, armature 45 and its resting contact, off normal springs 38, interrupter springs 41 and the winding of stepping relay 24 to battery. By current flow over the above circuit the stepping relay 24 is again energized and again closes the circuit of the rotary magnet 27 which in turn operates to advance the switch wipers into engagement with the next set of bank contacts. This operation continues as long as the test wiper 34 continues to engage grounded contacts. As soon as the first non-grounded test contact is reached, which we will assume to be the contact 43 associated with the trunk line comprising conductors 60 to 63, the stepping relay 24 will not again be energized, and the rotary movement of the switch will cease. The switching relay 25, which heretofore has been short circuited is now energized over the following circuit: grounded release conductor 36, winding of relay 25, off normal springs 38, interrupter springs 41 and the winding of relay 24 to battery. Relay 25 is of such high resistance that the stepping relay 24 is not energized at this time. Upon energizing relay 25 connects the test wiper 34 to the grounded conductor 36 in order to make the multiples of the test contact 43 busy to other switches, opens a point in the circuit of the release magnet 26 at armature 29, and at armatures 46 and 47 disconnects the line relay 21 from in bridge of the trunk line Y and substitutes the conductors 60 and 62 across which are bridged the windings of line relay 63 of the connector H. Line relay 63 is energized and completes a circuit for slow acting release relay 64. Upon energizing, relay 64 connects ground at its armature 78 to the release trunk conductor 61. It will be understood that this ground is applied before the slow release relay 22 in the selector D has deenergized, and therefore this latter switch 130

is prevented from releasing at this time and the lamp 8 continues to glow. Relay 64 also at its armature 82 prepares a circuit for the series relay 65 and vertical magnet 72 in the usual manner.

The B operator may now operate the calling device C. D. for the next digit of the desired number. By this operation a series of interruptions is produced in the circuit of the line relay 63. At each deenergization, an impulse of current is sent over a circuit extending from grounded armature of relay 63 and its resting contact, armature 82 and its working contact, off normal springs 83 and 85, and the windings of relay 65 and vertical magnet 72 to battery. The above is the circuit over which the first impulse to the vertical magnet is sent. Upon the first vertical step of the switch, the off normal springs are shifted and the remaining impulses to the magnet traverse a new circuit which is the same as the one above traced except that it includes the off normal springs 83 and 84 and armature of relay 65 and its working contact, relay 65 being now in an operated position. The vertical magnet 72 operates to raise the switch wipers 98 to 100 inclusive, step by step until they are placed opposite the level of bank contacts in which is located the contact set associated with the line of substation A. The slow acting relay 65 is energized in series with the vertical magnet 72 and maintains its armature attracted throughout the vertical movement of the switch, and at the termination thereof deenergizes, transferring the operating circuit to the rotary magnet 70.

The B operator may now dial the next and final digit of the desired number. As before a series of interruptions is produced in the circuit of relay 63 resulting in impulses of current being sent to the rotary magnet over a circuit extending from grounded armature and resting contact of relay 63, armature 82 and its working contact, off normal springs 83 and 84, armature of relay 65 and its resting contact, resting contact of armature 86' and the said armature, armature 94 and its resting contact, windings of slow relay 68 and rotary magnet 70 in multiple to battery. In response to these impulses the rotary magnet 70 operates to rotate the wipers 98, 99 and 100 into engagement with the particular set of bank contacts in which the line of substation A terminates, these contacts being the contacts indicated in the drawing by the reference numerals 86, 87 and 88.

The B operator having completed dialling the desired number she will now restore the key K⁵ to normal substituting the relays 12, 13 and 14 in bridge of trunk conductors 18 and 19 for the calling device C. D. The call is now completed so far as the B operator

is concerned, the lamp 8 however remaining lighted to indicate to the B operator that this trunk is in use.

It should be understood that in order to simplify the description, applicant has shown and described the impulse sending equipment at the B operator's position as a simple calling device manually connected and disconnected from the trunk by means of a key. In actual practice however, regular operator's impulse sending equipment will usually be used, such for instance as that shown in co-pending application of Martin L. Nelson Serial No. 492,976, filed August 17, 1921.

As a result of relays 12, 13 and 14 being bridged across the outgoing trunks, any one of three conditions may be indicated by the supervisory lamp 20 in the A operator's cord. If the selector D failed to find an idle trunk only relay 18 will be energized and lamp 20 will flash at the rate of 120 flashes per minute. If the selector succeeded in finding an idle trunk and the connection was completed to a busy called line, relays 13 and 14 will both be energized and lamp 20 will flash at the rate of 60 flashes per minute, while if the called line is idle the polarized relay 12 will energize resulting in the supervisory relay 15 being bridged directly across the trunk in substitution of relays 12, 13 and 14, causing the lamp 20 to glow continuously.

It will first be assumed that all trunks in the elected group were busy. This being the case magnet 27 of the selector D is therefore operated to move the wipers one step beyond the last trunk of the group. When this occurs the rotary off normal cam operates springs 48 and 48', and causes the ground through relay 20' to be substituted for direct ground, and causes also the circuit of relay 25 to be opened at contacts 48' to prevent the energization of relay 25 at this time.

The relay 20' energizes in series with relay 21, and in operating its armature cuts in its high resistance winding. The B operator of course does not know that all the trunks are busy and therefore the complete impulse series for operating the connector H will be transmitted. In this case these impulses will again operate the line relay 21 causing impulses to be again transmitted to the vertical magnet 28, but the vertical magnet will not effect the movement of the switch wipers as they have already been rotated. (This unnecessary operation of the vertical magnet may be easily avoided by placing rotary off normal springs in the vertical magnet circuit if desired.) It will be seen that each time the circuit of relay 21 is interrupted the high resistance winding of relay 20' will be shorted so that the reenergization of relay 21 is

always assured. This is essential as it will be seen that were the high resistance permanently cut in, the line relay might fail to again energize and the selector would be released, and the A operator would receive a false signal. When the impulses have all been transmitted and the B operator restores her key K', the high resistance of relay 20' being in series with the line relay 21 and relays 12, 13 and 14, marginal relay 14 and polarized relay 12 (relay 12 not being actuated until the current flow has been reversed) will not be operated. Relay 13 however pulls up and completes a circuit from battery, resting contact of armature 9 and the said armature, tip side of jack J', tip of plug P', upper springs of key K', upper right hand winding of repeating coil R, winding of relay 15, lower right hand winding of repeating coil R, lower springs of key K', sleeve of plug P', sleeve side of jack J', armature 16 and its resting contact, resistance 17, working contact and armature of relay 13, armature of relay 14 and its resting contact and the interrupter I to ground. The circuit of supervisory relay 15 in this instance has its circuit broken 120 times per minute causing the lamp 20 to be flashed accordingly. The A operator upon noting the rate at which the lamp is flashing will know that she cannot complete the call at this time and will remove the plug P' from jack J'. This first results in the de-energization of sleeve and trunk relays 11, 10 and line relay 21 of repeater D, followed by the release of relay 22. The retraction of armature 31 of relay 22 completes a circuit for the release magnet 26. This circuit extends from grounded resting contact of armature 29 and the same armature, armature 30 and its resting contact, armature 31 and its resting contact, off normal springs 25' and the release magnet 26 to battery.

The operator before withdrawing plug P from jack J operates her listening key K and informs the calling party that the call cannot be completed at this time, or she may again operate key 7 and again attempt to complete the call.

Assuming that the operator immediately calls again, and further that this time the called line is busy. After the final series of impulses have been transmitted to the rotary magnet 70, and before slow relay 68 de-energizes, a circuit is completed for the relay 67, from busy or grounded test contact 87, wiper 99, armature 88' and its working contact and the winding of relay 67 to battery. The relay 67 operates, and at its armature 102 prepares a locking circuit for itself which is closed when the relay 68 de-energizes a moment later. This locking circuit extends from the grounded test contact 87, wiper 99, armature 88' and its resting contact, armature 102 and its working contact

and the winding of relay 67 to battery. At its armature 86' it opens the operating circuit of relay 68 and rotary magnet 70 and at armature 101 opens a point in the operating circuit of relay 69. When the B operator restores the calling device key, battery from the line relay 63 of the connector H causes the energization relays 13 and 14. The operation of relay 14 switches the previously described circuit of relay 15 to the interrupter I'. The flashes to the A operator will in this case be at the rate of 60 per minute. The operator may either wait until the line becomes idle or may release the connection by withdrawing the plug P' as she sees fit. If she decides to wait, as soon as the line becomes idle ground will be removed from test contact 87 and battery substituted. When this occurs the relay 67 after a slight delay deenergizes and at armature 101 completes a circuit for relay 69, which may be traced as follows: from grounded working contact of armature 81 and the said armature, armature 101 and its resting contact, upper winding of relay 69, 90 wiper 99, test contact 87, winding of relay 90, interrupter contacts and winding of magnet 91 to battery.

Upon the closure of the above circuit relays 69 and 90 are energized in series, and the latter relay is operated to disconnect the line conductors 92 and 93 from their normal connections in the line switch C. Relay 90 is not completely operated because of the fact that the line relay of the line switch has not been energized and does not connect the line conductors with the wipers of the switch. In the connector H, the relay 69 upon energizing opens the circuit of the rotary magnet 70 at armature 94, establishes a locking circuit for itself at armature 103, connects ground to the test wiper 99 at armature 95, thus closing the circuit of relay 90 over a new path excluding the upper winding of relay 69 which was formerly included in the circuit, and at armatures 96 and 97 closes the signalling circuit thru to the line wipers 98 and 100. This circuit may be traced from interrupted generator Gen., lower resting contact and armature of ring cut-off relay 66, 115 armature 97 and its working contact, wiper 100, bank contact 88, conductor 93 to and thru the called line signalling apparatus, conductor 92, contact 86, wiper 98, working contact and armature 96, upper armature and resting contact of cut-off relay 66 and the upper winding of said relay to battery.

Relay 69 in operating at its armatures 75 and 76 also reverses the current flow in the calling line conductors. Referring to Fig. 1 the current flow being reversed polarized relay 12 now operates closing a circuit for relay 10, which operates and locks itself up independent of relay 12 and at its armatures 9 and 16 disconnects the relays 12, 13 and 14 130

from in bridge of the line and at the same armatures and their working contacts substitutes the supervisory relay 15. This relay energizes causing the lamp 20 to burn steadily. This signal informs the operator that the called line is now idle and is being signalled.

When the called subscriber responds the current flow thru the upper winding of ring 10 cut-off relay 66 is sufficiently increased to cause it to operate to disconnect the ringing current and to substitute the back bridge relay 73 in bridge of the called line. This relay operates and at its armatures 79 and 15 77 disconnects the line relay from the calling line conductors and maintains it energized in a local circuit. The removal of battery from the calling line conductors causes the supervisory relay 15 in the cord circuit O to 20 deenergize to extinguish the lamp 20, notifying the operator that the called subscriber has responded. The operator may now operate her listening key to further supervise the call as desired.

25 Had the line been idle at the time that it was seized the relay 67 would of course not have been operated and immediately upon the slow relay 68 restoring, the relay 69 would have operated to start the ringing and 30 to reverse the current flow in the calling line in the manner above described.

After the conversation has been completed the subscribers replace their receivers. Upon the subscriber A replacing his receiver the back bridge relay 73 deenergizes and again connects line relay 63 in bridge of the line. This causes the supervisory relay to again energize causing the lamp 20 to glow to inform the A operator that the conversation has been completed. The replacement of the receiver at the calling substation causes the usual supervisory signal at the operator's position at that exchange to be operated in well known manner.

45 The operator may now withdraw the plugs P and P' from their respective jacks. The removal of plug P' from jack J' removes the bridge from trunk conductors 18 and 19 causing line and release relays 63 and 64 to 50 deenergize to complete a circuit for release magnet 71, to restore the switch H to normal. Relay 64 in retracting its armature 78 also removes ground from switching relay 25 of the selector D, and from the lamp 8 at the 55 B operator's position. Relay 25 in restoring, at its armature 29 completes the previously described circuit for release magnet 26 causing release of the selector D. All apparatus is now at normal and in readiness to be seized for any subsequent calls, lamp 8 being extinguished, again indicating the idle condition of the trunk line to the B operator.

What is claimed is:

65 1. In a telephone system, a manual office

and an automatic office interconnected by trunk lines, an operator's cord circuit at the manual office for completing calls to subscribers of either office, means for providing order wire service between said offices to permit an operator at the manual office to repeat numbers of subscribers in the automatic office to an operator thereat and to permit such operator to assign one of said idle trunks to the manual operator, automatic switches in the automatic office for setting up connections to called lines, means at the automatic office for transmitting impulses to effect the operation of said automatic switches, and supervisory means at the 75 manual office operative in a characteristic manner depending upon the number of automatic switches operated, or the condition of the called line when seized.

2. In a telephone system, a manual office 85 and an automatic office, a trunk line extending between operator's positions in said offices and also having a branch terminating in an automatic switch in the latter office, means for seizing said trunk line at the 90 manual office, means at the automatic office for controlling said automatic switch to select a particular group of trunk lines and to hunt for an idle trunk in that group, a group of controlling relays in the manual 95 end of said first trunk, and means in said automatic switch effective when all of a trunk group are busy for preventing the operation of a particular one of said relays while permitting the operation of another 100 of said relays to control a supervisory signal at the manual office in a distinctive manner.

3. In a telephone system, a trunk line having one end terminating in a jack and the other end terminating in an automatic 105 switch, means at an intermediate point in said trunk line for disconnecting the portion of the trunk terminating in the jack and for controlling the movement of said switch over the other portion, other automatic switches accessible to said first switch and having access to called lines, the means for controlling the first switch also being adapted to control said other switches, a cord circuit for extending connections to 110 said trunk line, a signal in said cord, and means in said trunk for variably operating said signal to inform an operator whether the line has been seized or not and the condition of the called line if seized.

4. In combination, a cord circuit, a trunk line, a series of automatic switches and a called line, means associated with said trunk line for transmitting impulses for positioning said automatic switches to set up a connection with said called line, a signal in said cord circuit, and means in said trunk effective in a manner dependent upon the number of automatic switches operated or upon the condition of the called line when seized 125 130

to cause said signal to operate in a distinctive manner to indicate in any case the exact number of switches operated and to indicate whether the called line is busy or idle in case 5 all said switches are operated.

5. In a telephone system, an operator's switchboard in a manual office, an operator's switchboard in an automatic office, a trunk line connecting said switchboards and also 10 having a branch terminating in an automatic switch in said automatic office, other automatic switches, auxiliary means of communication between said switchboards for permitting an operator at the manual office to 15 repeat called numbers to an operator in the automatic office, means at the switchboard of the latter office for controlling said automatic switches to extend connections to called lines, a supervisory signal at the manual office, and means in said trunk for operating said signal in two distinctive ways upon failure of the call and operable in still another way if the call is successful.

6. In a telephone system, a toll office, an 25 automatic exchange, an interconnecting trunk line terminating in a selector at the automatic exchange, groups of connectors accessible to said selector, means at the automatic exchange for operating said selector to 30 select a group of connectors and an idle connector in the group and for then operating the selected connector to connect with a called line, a signal at the toll office, and means including three relays in a bridge of 35 said trunk for operating said signal in three different ways depending on whether the desired group of connectors is busy, and on whether the desired called line is busy or idle.

40 7. In a telephone system, a toll office, an automatic exchange, an interconnecting trunk line terminating in a selector at the automatic exchange, groups of connectors accessible to said selector, means at the automatic exchange for operating said selector to 45 select a group of connectors and an idle connector in the group and for then operating the selected connector to connect with a called line, a signal at the toll office, said 50 signal comprising a lamp, a relay for flashing said lamp if the selector fails to find an idle trunk line in the selected group, means including a marginal relay in series with said first relay for flashing said lamp in a 55 different way if the called line is busy, and means for lighting the lamp steadily if the called line is idle.

8. In a telephone system, a trunk line extending from a toll office to an automatic 60 office, a signal, a supervisory relay controlling said signal, three relays bridged across said trunk line, a steady energizing circuit for the supervisory relay controlled by one 65 of said three relays, a flashing circuit for said supervisory relay controlled by another

of said three relays, a different flashing circuit for said supervisory relay controlled by the other of said three relays, and means in the automatic office for controlling said three relays over the trunk line.

70

9. In a telephone system, a trunk line comprising two sections, two interrupters operating at different speeds, a bridge across one of said sections, and relays in said bridge selectively controlled to associate either of 75 said interrupters with the other of said sections.

10. In a telephone system, a trunk line comprising two sections, two interrupters operating at different speeds, a bridge across 80 one of said sections, relays in said bridge selectively controlled to associate either of said interrupters with the other of said sections, and a polar relay also included in said bridge for controlling the connecting 85 of said sections together.

11. In a telephone system, a selector having a line relay, a circuit for said relay, a second relay having two windings, means actuated in the operation of said selector 90 for including one winding of said second relay in said circuit, and contacts on said second relay for including its second winding in said circuit also.

12. In a telephone system, a trunk hunting 95 switch, two energized relays, a resistance unit, and contacts operated responsive to a movement of said switch beyond its trunking range for inserting said unit in series with said relays whereby one relay falls back and the other remains operated.

13. In a telephone system, a trunk hunting 100 switch having a line conductor, a line relay having a winding connected to said conductor, a resistance unit having a resistance substantially higher than the resistance of said winding, and contacts operated responsive to a movement of said switch beyond its trunking range for inserting said unit in series with said winding.

105

14. In a connector switch, a line relay and means controlled thereby for operating the switch to connect with a called line, incoming trunk conductors terminating in said relay, a switching relay operated when the called line is connected with to reverse said conductors with respect to the line relay windings, and a battery feed relay in said connector operated when the called party answers for disconnecting said conductors 115 from said line relay.

110

15. In a connector switch, a line relay and means controlled thereby for operating the switch to connect with a called line, incoming trunk conductors terminating in said 125 relay, a switching relay operated when the called line is connected with to reverse said conductors with respect to the line relay windings, a battery feed relay in said connector operated when the called party 130 answers for disconnecting said conductors from said line relay.

- swers for disconnecting said conductors from said line relay, and contacts on said battery feed relay for closing a local circuit to maintain said line relay energized.
16. In a connector switch, a line relay and means controlled thereby for operating the switch to connect with a called line, incoming trunk conductors over which said line relay is controlled, a relay in said connector operated when the called line is connected with to reverse the direction of current flow in said conductors, and another relay in said connector controlled over the called line to stop the flow of current in said conductors.
17. In a telephone system, a trunk line having one end terminating in a jack and the other end terminating in an automatic switch, means at an intermediate point in said trunk line for controlling the movement of said switch over the trunk line, other automatic switches accessible to said first switch and having access to called lines, said last mentioned switches being controlled by way of said first mentioned switch, a cord circuit for extending connections to said trunk line, a signal in said cord circuit, and means in said trunk for variably operating said signal to indicate whether a called line has been seized and to indicate the condition of the line if it has been seized.
18. In a telephone system, a trunk line having one end terminating in a jack and the other end terminating in an automatic switch, means at an intermediate point in said trunk line for transmitting groups of digit impulses over the trunk line to extend a connection to a desired station, a cord circuit for extending connections to said trunk line, a signal in said cord, and means in said trunk for variably operating said signal to indicate to an operator which was the last group of digit impulses to be effective to extend the connection from the trunk line.
19. In a connector switch, a line relay, means controlled thereby for operating the switch to connect with a called line, incoming trunk conductors over which said line relay is controlled, said relay applying a potential to said conductors, a relay in said connector operated when the called line is connected with to reverse the direction of the potential applied to said conductors, and means operated when the called party answers for removing said potential from said conductors.
20. In a telephone system, a selector having a line relay, means for establishing a circuit for said line relay, two resistors, means actuated in the operation of the selector for including one of said resistors in said circuit, and means effective responsive to the insertion of said one resistor in said circuit for including the second resistor in series with the first resistor.
21. In a telephone system, the combination with a telephone line, of an automatic switch, groups of trunk lines terminating at said switch, an operator's position, a signal lamp thereat, means for operating said switch to select a desired group of trunks, means in said switch automatically effective to select an idle trunk in the selected group of trunks, and for extending the line over the selected trunk, means effective if the switch fails to find an idle trunk for inserting a resistor in series with the line, a marginal relay in series with the line, said marginal relay being inoperative in series with said resistor, means controlled by the marginal relay for flashing the lamp in a predetermined manner, and means controlled by the marginal relay under predetermined conditions upon the selection of an idle trunk in the selected group for flashing said lamp in another manner.
22. In a telephone system, a line terminating in a selector including a line relay, said selector having access to a plurality of groups of trunks each of which trunks terminates in an automatic switch, means for transmitting digit impulses to the line relay of the selector to cause the selector to select a desired group of trunks, means for automatically operating the selector to select an idle trunk in the selected group, means effective responsive to the selector failing to find an idle trunk for inserting a resistor in series with the line relay, means responsive to subsequent digit impulses transmitted to the line relay for periodically removing and reinserting said resistor in said circuit, said resistor being excluded from the circuit when the line relay is released by the digit impulses and included in the circuit when the line relay is operated by the digit impulses, whereby the periodic operation of the line relay is assured, and signalling means controlled by said resistor for indicating whether an idle trunk has been found.
23. In a telephone system, a manual exchange, an automatic exchange, a trunk connecting the two exchanges and terminating in a selector at the second exchange, said selector having access to groups of trunks, a cord at the first exchange for extending a connection to said first named trunk, means at the second exchange for transmitting digit impulses to the selector for operating the selector to select a desired group of trunks, said selector being automatically operable to select an idle trunk in the selected group, a marginal relay and a supervisory signal at the first exchange, and means at the second exchange for controlling the marginal relay to operate the signal to indicate whether an idle trunk in the selected group of trunks has been found.
24. In a toll switching system, a toll operator's position, an incoming toll trunk ter-

minating at said position, automatic switches accessible from another operator's position, order wire service between the two positions, a trunk connecting the two positions, dialling equipment at the second operator's position for extending a connection from the last mentioned trunk, and a toll cord circuit at the first mentioned position for connecting the incoming toll trunk with the last mentioned trunk.

25. In a telephone system, a toll board at which incoming calls are received, an automatic exchange, a toll switching train comprising automatic toll switches at said exchange, a dialling operator's switchboard, a trunk extending from said toll board to said automatic exchange, means at said switchboard whereby the operator thereat may control the operation of said automatic toll switches over said trunk in accordance with

the number of a called line as communicated to her by the toll operator at the toll board, and means at said toll board whereby the toll operator may complete the toll call over said trunk.

25

26. In a telephone system, an exchange, a toll switchboard at said exchange, a special dialling operator's switchboard, an automatic exchange, trunks extending from said toll switchboard to said automatic exchange, automatic switches at said automatic exchange, means at said dialling operator's switchboard for controlling the operation of said automatic switches over any one of said trunks, and means at said toll switchboard for completing a toll connection over the trunk used.
